UNITED STATES PATENT OFFICE.

FRIEDRICH WILHELM HORST, OF NECKARGEMUND, GERMANY.

SEALED PACKAGE.

Application filed June 4, 1923, Serial No. 643,292, and in Austria June 6, 1922.

- Hitherto it has been regarded as an axiom, in chemical science and technics, that normal solutions can only be produced according to well settled principles laid down for that purpose, namely by a standard solution; such standard solutions, however, are confined to few substances, available with a sufficient degree of purity. The normal solutions have been standardized according to the standard solutions, and in view of the small number of standard substances this involved considerable difficulty, everything depending on the accuracy of the indicator. Consequently normal solutions have generally been made by the individual user. It would certainly have created great surprise among experts if the assertion had been made that normal solutions could be made without recourse to standard solutions, and without the complicated methods of observation and control hitherto in vogue, and the astonishment would have been greater if it were said that the care hitherto prescribed could be discarded, and that certain steps in the method of procedure could be undertaken separately, as regards time and place. As a matter of fact, the principles hitherto laid down were never properly tested in regard to their actual validity, and it has merely been assumed that psychologically and physiologically no person is capable of performing scientific measurements with a degree of accuracy exceeding a narrow individual limit.
- The present invention is based, firstly, on recognition of the fact that this assumption of psychological and physiological inadequacy is not justified, and secondly on ascertainment of the fact that normal solutions can indeed be produced without the complicated methods of procedure hitherto in vogue, and with certain steps in the process separated as regards time and place, without special checks or controls.
- As a result of experiments extending over years, and required to collect the material opposed to the views hitherto entertained, I am now enabled to produce normal solutions by a considerably modified and shorter method, on a manufacturing scale, the basic materials, whether solid or liquid, being dealt with by factory methods, and being easy to transport, and capable of use in any climate or place.
- The present invention comprises fire-sealed glass containers having an integral frangible
- re-entrant bottom and containing a very carefully measured quantity of a solute which, when the contents are mixed with a definite quantity of a solvent, forms a normal solution. The substances (of known composition) for preparing the desired normal solutions are protected from the action of the atmosphere as they are closed airtight in the containers. Thus, at any time and at any place by merely dissolving the substance accurate normal solutions, directly ready for use, are obtained. For use the container is opened and the contents is introduced into the usual beaker or flask and dissolved to the desired strength by means of the usual solvent, say water. No special adjustment or check whatever is required.
- Normal solutions have heretofore been produced on a manufacturing scale, but the delivery thereof was limited to a comparatively small radius, due to the bulk of the package, as a small quantity of material required a large quantity of water, a large bottle or flask, weighing more than the water, and a bulky envelope to protect it from blows and pressure. Other disadvantages arose from sending out the materials in solution. In aqueous solutions which are not made with water or preparations entirely free from bacteria there is always risk of organic growths in the form of mould and the like. The more often a bottle containing normal solution is opened, the greater is the risk of some change in the solution.
- A minute quantity of the dissolved preparation required an enormous proportion of dead weight in transport. This is disposed of by the invention. There is merely the weight of the preparation itself, and of the light container, so the dead weight is reduced to the smallest limit. Where heretofore heavy packages were involved, sent by freight train, the materials can now be sent by post, with much saving of time. Twenty small tubes, with protective wrappers, for making twenty liters of normal solution, weigh less than 5 kg.
- The method of preparation saves much of the consumer's time, and the scientific control introduced opens up possibilities of important developments.
- Besides for producing preparations for use in analysis the method is also useful for preparing colours and dyes in solutions of definite strength, and for the accurate dosage of pharmaceutical preparations, pre-

cluding errors in the making up of prescriptions.

For the gravimetric analytic determination of nitrite, weighed quantities of sulfanilic acid are used, and for testing the purity of double salts, diazotized aromatic amines; vice versa, these compounds can be determined with accurately weighed quantities of nitranilin.

10 A modification of the methods in weighing the substance in a state of intimate mixture with a substance which facilitates the weighing operation, for example a neutral salt, or colloid or the like. The weighing and filling of the container may be performed in an atmosphere of inert gas, for example in a box filled with nitrogen or carbon dioxide. The weighing may be performed by taking somewhat more than the estimated 15 mass and removing the excess by suction, till the scale balances.

The glass containers chiefly used are preferably made sufficiently thin, at the part where the contents are to be removed, to be 20 broken by light pressure, the weakened part being in an indentation or recess. There may be more than one such weakened part. A suitable place therefor is the bottom of the flask, made with an indentation somewhat 25 like that of the wine bottle. The best method is generally to have at least two fragile parts, so that one can be used for flushing purposes. The opening of the container can be performed by tapping the 30 weak part with a suitable tool. The weak part being within a recess, the fracture is not liable to occur accidentally in course of transport. If the weak part is at the bottom 35 of the flask, the latter is of course inverted while the fracture is made. When it is then 40 inclined to pour out the liquid, the edge left around the hole retains the fragments of broken glass.

If it is very important to prevent any 45 fragment of glass from coming out, for example in the case of an article of food, a filter plug may be inserted into the hole made, or a cup like vessel, having a spout and lined with a filtering material such as 50 spun glass, may be inserted into the opening of the flask.

A suitable tool for opening the flask is a mandrel connected with a funnel or cup adapted to receive and lead away the liquid issuing from the hole made. Such cup or funnel may be shaped for the flask to fit conveniently into it. The mandrel is fitted into the discharge pipe or tube so as to have adequate guidance therein and so that it cannot 60 be shifted from its most convenient position. It is sharpened towards the top, considerably widened at the part where it rests, on the cup and shaped at the bottom like a 65 lance rod. In the case of a short cap the mandrel may project from the tube and be

thickened at the lower part so that it does not fall out.

Generally a sufficient joint is made, by the contact, to prevent fragments of glass from coming out, or the mandrel may be ground to fit with precision. For better conduction of the liquid, channels or ribs may be provided. The mandrel may be fused rigidly to the discharge funnel, in which case discharge holes must be provided.

If only one opening is made in the flask, the outflow is slow, as air can only enter with difficulty. This can be avoided by making the mandrel tubular, with holes which admit air to the space above the liquid. In any case the discharge pipe may have a filter therein.

In the case of a plurality of substances to be combined in solution, there may be a plurality of flasks, one within the other, arranged to be opened collectively.

A few preferred methods of carrying the invention into effect are illustrated in Figs. 1 to 8 of the annexed drawings.

Fig. 1 shows a flask with a weakened part at its concave bottom *a* and a dent *b* near the top.

Fig. 2 illustrates the opening of the flask at the bottom by means of a mandrel *c* operated by hand, thrust in while the flask is inverted, so that the glass fragments drop down to the neck. When the flask is inclined (Fig. 2^a), for pouring out the liquid, the fragments are retained by the edge 95 around the hole.

Figs. 3 and 3^a illustrate the use of a filter plug to prevent glass fragments from becoming mixed with the liquid poured out, for example if it is an article of food. In Fig. 3 the flask is shown open, ready for insertion of the filter plug *d*, for example a plug of spun glass. Fig. 3^a shows the flask in position for emptying it.

In Fig. 4, *e* is a cap with a discharge pipe *f*, into which fits a mandrel *g*, usually of glass. This mandrel is pointed at the top and thickened at the middle, to rest on a restricted part of the cap. At the bottom there is a thin extension guided in the funnel tube, and thickened at *h* to prevent it from falling out. The extension, which is as thin as possible, holds the mandrel in the proper axial position for making the fracture. It is intended that the part *g* shall only make good contact at the joint. For 110 the better flow of the liquid it is shown, in Fig. 5^a, with grooves.

According to Fig. 5 a funnel like vessel *i*, forming a kind of elongated cap, is inserted into the flask, so flushing can be performed in order to thoroughly empty the flask. For that purpose it is of advantage to break also a weak portion at the top of the flask. The fragments of glass are retained by the mandrel, especially if it fits well.

Other modifications are shown in Figs. 6 and 7. In Fig. 6 the mandrel is fixed, and Fig. 7 shows to an enlarged scale a loose, hollow mandrel admitting air to the flask 5 from the bottom, during the pouring out.

Fig. 8 shows two flasks, one within the other, for different substances, and having weakened portions, in register, at the bottom, for simultaneous fracture.

16 The appliances described and illustrated enable substances to be sold in flasks in many cases where this was formerly not practicable. The devices shown for the purpose enable the opening to be performed

15 by unskilled persons without risk of wasting the valuable contents. As indicated, the flasks can be used also for solid substances, which can be flushed out if a second opening is made.

20 The thin, fragile parts can be produced in the known manner, in the course of blowing the glass. With the funnel appliance, the flask need only be dropped into the guide way therefor, and the fracture will occur 25 automatically. The funnel is placed upon a graduated beaker or the like, and a normal solution of the substance prepared as described can thus easily be prepared.

Having now particularly described and 30 ascertained the nature of my said invention and in what manner the same is to be performed, I declare that what I claim is:

1. A fire sealed glass container having an integral frangible re-entrant bottom and 35 containing a very carefully measured quantity of a solute sufficient when mixed with a definite quantity of a solvent to form a normal solution.

2. A sealed package comprising a fire 40 sealed glass container having a re-entrant portion frangible at its greatest depth and

containing a very accurately measured quantity of a solute capable of forming with a carefully measured quantity of a solvent, a normal chemical solution.

45

3. A sealed package comprising a fire sealed glass container, having a re-entrant frangible bottom and containing a very accurately measured quantity of a solute, and also containing a second fire-sealed glass 50 container containing a very accurately measured quantity of a second solute, said solutes forming when mixed with a measured quantity of solvent, a normal chemical solution.

55

4. The combination with a funnel having a flaring top, terminating with a portion for receiving a receptacle said portion ending in a restricted tubular part and a mandrel held in the funnel by said restricted part; of a 60 fire sealed glass container arranged to enter said portion and be pierced by said mandrel to discharge its contents into said funnel.

5. The combination with a funnel having a conical top, terminating in a portion for 65 receiving a receptacle said portion ending in a discharge part of smaller cross-section and a tubular mandrel held in the funnel by said part of smaller cross section; of a fire sealed glass receptacle having a re-entrant frangible portion at one end engaged by said mandrel.

70

6. A closed container, comprising an integral, frangible re-entrant bottom containing an accurately measured quantity of a 75 solute, which when mixed with a definite quantity of a solvent will produce a normal solution, said container also having a frangible portion near its upper end.

In testimony that I claim the foregoing as my invention, I have signed my name.

Dr. FRIEDRICH WILHELM HORST.
